Primary Examiner — Mitchell Siegel(74) *Attorney, Agent, or Firm* — Ohlandt, Greeley, Ruggiero & Perle, LLP**CLAIM**

It is claimed the ornamental design for the ice machine, as shown and described.

DESCRIPTION

FIG. 1 is a front view of an ice machine according to the present invention;

FIG. 2 is a rear view of the ice machine of FIG. 1;

FIG. 3 is a side view of the ice machine of FIG. 1;

FIG. 4 is a side view of the ice machine of FIG. 1 that is opposite the side view of FIG. 3;

FIG. 5 is a top view of the ice machine of FIG. 1;

FIG. 6 is a bottom view of the ice machine of FIG. 1; and, FIG. 7 is a top side perspective view of the ice machine of FIG. 1.

The broken lines in the drawings illustrating environmental structure form no part of the claimed design.
